DESIGN FOR A TABLE-COVER OR CURTAIN.

UNITED STATES PATENT OFFICE.

EDWARD POOLE, OF PHILADELPHIA, PENNSYLVANIA, ASSIGNOR TO JOHN BROMLEY & SONS.

DESIGN FOR A TABLE-COVER OR CURTAIN.

SPECIFICATION forming part of Design No. 21,335, dated February 2, 1892.

Application filed March 7, 1891. Serial No. 384,159. Term of patent 3½ years.

To all whom it may concern:

Be it known that I, EDWARD POOLE, a subject of the Queen of Great Britain, residing at Philadelphia, in the county of Philadelphia and State of Pennsylvania, have invented a certain new and original Design for a Table-Cover or Curtain, of which the following is a specification, reference being had therein to the accompanying drawing.

10 My invention relates to the surface ornamentation of a table-cover or curtain usually applied to a woven chenille fabric; and it consists of the design therefor illustrated in the accompanying photographic drawing, its leading features being the leaf-like border A, the field-center ornamentation consisting of three floral pyramids B B' B² within the said border, and the supplemental floral ornamentation C within the said border A at one end only of the curtain. That end of the curtain containing the supplemental ornamental figures C is shown thrown over a curtain or portière pole.

I claim as my invention—

1. The design for a table-cover or curtain, substantially as shown and set forth.
2. The design for the border A of a table-cover or curtain, substantially as shown and set forth.
3. The design for the ornamental figures B B' B² within the border, substantially as shown and set forth.

In testimony whereof I have affixed my signature in presence of two witnesses.

EDWARD POOLE.

Witnesses:

ADOLPH PETZOLD,
EDWARD BROMLEY.
